UNITED STATES PATENT OFFICE.

ALPHONSO S. CAMPBELL, OF WEST MEDFORD, MASSACHUSETTS, ASSIGNOR TO A. S. CAMPBELL COMPANY, OF BOSTON, MASSACHUSETTS, A CORPORATION OF MASSACHUSETTS.

METHOD OF MAKING RINGS AND THE LIKE.

1,426,275.

Specification of Letters Patent. Patented Aug. 15, 1922.

Application filed April 6, 1921. Serial No. 459,115.

To all whom it may concern:

Be it known that I, ALPHONSO S. CAMPBELL, a citizen of the United States, and resident of West Medford, in the county of Middlesex, State of Massachusetts, have invented an Improvement in Methods of Making Rings and the like, of which the following description, in connection with the accompanying drawings, is a specification, like characters on the drawings representing like parts.

This invention pertains to improvements in methods of making rings and the like from sheet metal. It is among the objects of the invention to provide a method whereby rings and the like may be formed from relatively thin sheet metal, while minimizing the trouble and loss of material arising from operations during manufacture of the article.

I have found my new method peculiarly useful in connection with the manufacture of relatively large rings such as are used as portions of the frames of curtain windows.

In the drawings which show a preferred embodiment of one form of my invention as applied to the manufacture of parts of curtain window frames:—

Figure 1 is a front elevation of a portion of a curtain window frame in process of manufacture;

Fig. 2 is a rear elevation thereof;

Fig. 3 is a section on the line 3—3 of Fig. 1;

Fig. 4 shows sections of the parts shown in Fig. 3 prior to assembly; and

Fig. 5 is a section of a completed ring.

Referring to the drawings and to the preferred form of my invention selected for illustrative purposes, I have shown in Fig. 5 a section of a completed ring including the outer ring part 6, stiffened by a stiffening element 7. In practising the preferred form of my improved method, I initially stamp on a piece of sheet metal the desired ring, while leaving the center portion of the metal to stiffen the ring. In Fig. 4, is shown a cross-section of the ring 6 having the center portion 8 left as a stiffening member. The ring 6 is preferably, as indicated, convex on one side and concave on the other. The stiffening element 7 may be of any suitable form, but is preferably, as illustrated, formed from sheet metal distorted by stamping or the like to provide a relatively stiff cross-section, such as the right-angle cross-section

illustrated in the drawings. This reinforcing part preferably fits into the concave recessed side of the ring and may be attached to the ring in any suitable way, but preferably, as illustrated, by spinning or dieing over the peripheral portion of the ring 6 as indicated at 9. If desired, the ring may be buffed, holes tapped in the reinforcing element, or any other desired operation performed while the stiffening element 8 is still in place. The stiffening element 8 may then be punched out, leaving the ring 6 reinforced by the stiffening element 7 of sufficient strength to withstand subsequent operations, if any. If, as in the ordinary course of manufacture, the metal 8 in the center portion of the ring were stamped out as a part of the initial operation of forming the ring 6, great difficulty would be encountered in properly assembling the ring 6 and the stiffening member 7, this arising from the inherent flexibility and lightness of the ring 6.

Whereas in the case of a curtain window, the stiffening element 7 performs additional functions and it is desirable to have holes punched therethrough; these holes may be punched prior to assembly with the other portions of the ring.

While I have illustrated a preferred product made by my improved method, and while I have described a preferred method of practising my invention, it will be understood that considerable changes may be made without departing from the scope of my invention, which is best defined in the following claims.

Claims.

1. The method of making rings and the like from sheet metal, which comprises stamping on the sheet the desired ring while leaving the center portion of the metal to stiffen the ring, reinforcing the ring by assembling therewith a stiffening member and subsequently removing the center portion.

2. The method of making rings and the like from sheet metal, which comprises stamping on the sheet the desired ring while leaving the center portion of the metal to stiffen the ring, reinforcing the ring by assembling therewith a stiffening member by distorting the margin of the ring to overlie the stiffening member and subsequently removing the center portion.

3. The method of making rings and the like from sheet metal, which comprises stamping on the sheet the desired ring, said

ring concave on one face and convex on the other, while leaving the center portion of the metal to stiffen the ring, reinforcing the ring by assembling therewith on the concave side 5 a stiffening member and subsequently removing the center portion.

4. The method of making rings and the like from sheet metal, which comprises stamping on the sheet the desired ring, said 10 ring concave on one face and convex on the

other, while leaving the center portion of the metal to stiffen the ring, reinforcing the ring by assembling therewith on the concave side 15 a stiffening member by distorting the margin of the ring to overlie the stiffening member and subsequently removing the center portion.

In testimony whereof, I have signed my name to this specification,

ALPHONSO S. CAMPBELL.
